MANIPULATING ATTACHMENT FOR THE LENS FOCUSING MECHANISM OF MOVING
PICTURE PROJECTING MACHINES

Application filed October 2, 1928. Serial No. 309,841.

This invention relates to a manipulating device for the lens focusing mechanism of moving picture projecting machines, the same being in the nature of an attachment which is especially applicable to the Simplex projector.

Up to the present time the lens focusing mechanism has been actuated by direct manipulation of a knurled head on the vertical shaft of a pinion which engages a rack connected to the lens. In addition to the fact that a precise or accurate adjustment is difficult to obtain, the knurled head which is disposed at a point or a position at the left 10 side of the projector, is difficult for the operator to reach from his station on the right side of the machine.

In order, therefore, to overcome the above recited difficulties and disadvantages, the 20 present invention comprehends a manipulating attachment by virtue of which a more precise and accurate adjustment may be obtained and which, in addition, disposes the manipulating head at a point convenient to 25 the operator's station.

The invention further comprehends a manipulating attachment of the character set forth which is extremely simple in its construction, inexpensive to manufacture, 30 highly efficient in its purpose and which may be readily installed on the machine without material alteration thereto.

With the above recited and other objects in view, reference is had to the following description and accompanying drawings, in 35 which there is exhibited one example or embodiment of the invention, while the claims define the actual scope of the same.

In the drawings:

40 Figure 1 is a rear end view of the lens housing with the attachment applied.

Figure 2 is a side view thereof.

Figure 3 is a plan view illustrating a slightly modified adaptation of the invention.

45 Referring to the drawings by characters of reference, A designates the lens housing, B the lens, C the lens adjusting rack, D the pinion, and E the pinion shaft which extends vertically upward through the upper wall of

the lens housing. Ordinarily, a knurled head is secured to the upper end of the pinion shaft E for direct manipulation of the pinion to accomplish the forward and rearward movement of the lens for proper focusing on 55 the screen. Obviously, in addition to the difficulty experienced in obtaining the proper focus, the knurled head for manipulating the same is disposed in a position on the left side of the projector, whereas the operator is 60 usually stationed on the right side. The present attachment for manipulating the pinion shaft E consists of a bracket arm 5 which is formed with an apertured extremity 6 adapted to be positioned over the upper 65 end of the pinion shaft E after the usual knurled manipulating head had been removed. The bracket arm 5 is provided with upstanding bearing gears 7 and 8 in which a manipulator shaft 9 is journaled for rotation. 70 A worm gear 10 is keyed to the pinion shaft E and is designed to mesh with a worm wheel 11 keyed to the manipulator shaft 9. The bracket arm 5 is further provided with a forwardly projecting horizontal lug 12 75 which is secured by a screw 13 to the upper wall of the lens housing A. The right end of the manipulator shaft 9 has secured thereto a knurled manipulating head 14, and in view of the fact that the bracket arm extends 80 from the pinion shaft E toward the right, it is obvious that the knurled head 14 is disposed within convenient reach of the operator's station at the right hand side of the projecting machine. The worm pinion and 85 wheel connection permits of a micrometer adjustment of the lens B so that a precise and accurate focusing may be obtained.

In the modified form of the invention illustrated in Figure 3, the bracket bar 15 is of a length to extend beyond the medial apertured lug 16 through which the pinion shaft E projects, and in this instance the manipulator shaft 17 is lengthened so that its opposite ends extend through upstanding end bearing ears 18 and 19 in addition to a medial bearing ear 20. Knurled heads 21 and 22 are secured to the opposite ends of the manipulator shaft, and the worm gear 23 meshes with a worm gear 24 keyed to the intermediate portion of 100

the manipulator shaft. Under this construction, it is obvious that the micrometer adjustment of the lens may be accomplished by manipulation of either of the heads 21 or 22.

5 What is claimed is:

1. The combination with a moving picture projecting machine having a lens focusing mechanism including a rack, a pinion and an upwardly extending pinion shaft projecting 10 through the lens housing, of a manipulating attachment therefor comprising a bracket arranged transversely upon the housing having a horizontally disposed apertured portion through which the projecting end of the 15 pinion shaft extends, a worm gear secured to the end of said pinion shaft, a manipulator shaft journaled in bearings in the bracket, a worm wheel secured to said manipulator shaft and meshing with the worm gear and a 20 manipulator head at the end of the manipulator shaft.

2. The combination with a moving picture projecting machine having a lens focusing mechanism including a rack, a pinion and an 25 upwardly extending pinion shaft projecting through the lens housing, of a manipulating attachment therefor comprising a bracket arranged transversely upon the housing having a horizontally disposed apertured portion 30 through which the projecting end of the pinion shaft extends, a worm gear secured to the end of said pinion shaft, a manipulator shaft journaled in bearings in the bracket, a worm wheel secured to said manipulator shaft 35 and meshing with the worm gear and a manipulator head at the end of the manipulator shaft, said bracket having a horizontally disposed lug adapted to receive therethrough 40 a fastening element for anchorage in the lens housing.
